UNITED STATES PATENT OFFICE.

JOSEPH H. DICKINSON, OF WINTER PARK, FLORIDA, ASSIGNOR TO LIDGERWOOD MANUFACTURING COMPANY, OF NEW YORK, N. Y., A CORPORATION OF NEW YORK.

OVERHEAD CABLEWAY SYSTEM.

Application filed June 15, 1927. Serial No. 198,930.

This invention relates to a novel and improved cableway system particularly adapted for use where it is desired to reach material to be handled which is situated in a 5 valley or canyon. The invention will be best understood from the following description and the accompanying drawings in which

Fig. 1 is a diagrammatic section through 10 a canyon or valley, showing one form which my invention may take.

Fig. 2 is a view similar to Fig. 1, showing a modified form of the invention.

Fig. 3 is a diagrammatic view of the 15 means for operating the system.

Fig. 4 is a fragmentary view similar to Fig. 1, but showing other positions which certain of the parts may take.

Referring first to Fig. 1, my invention 20 comprises a main cable 1, which is suitably secured to the head mast 2, and the tail mast 3. These masts may be any of the usual devices employed for the purpose, but are herein shown as trunks of trees. Running 25 on the main cable is a carriage which is shown herein as comprising a trolley section 4, provided with wheels 5, to engage the main cable, and a drop section 6. This section is capable of being raised and lowered 30 in respect to the trolley section, as by means of the lifting cable 7 which is shown as being secured at one end to the tail mast and running over sheaves 8 on the trolley section, and a sheave 9 on the drop section of 35 the carriage. The lifting cable is then passed over a sheave 10 on the head mast and wound upon a drum 11.

An outhaul cable 12, is connected to the drop section and is carried therefrom over 40 a sheave 13 at the tail mast and thence over a sheave 14 on the head mast and wound upon drum 15. A skidding cable 16 is wound upon a drum 17, and passes over a sheave 18 upon the head mast and a second sheave 19 45 upon the drop section of the carriage. The end of the skidding cable is provided with a suitable working implement which is herein illustrated as a pair of tongs 20 for engagement with a log 21. It is to be understood that any other desired implement may 50 be employed in place of the tongs.

A slack pulling cable 22 is connected to the skidding cable and runs over a sheave 23 on the drop section 6 and thence over a

sheave 24 on the head mast and is wound 55 upon a drum 25. This arrangement of skidding cable and slack pulling cable per se, is well known in the art.

It will be understood that the various drums are operated in any suitable manner 60 and the details of their operation have been omitted because they form no part of this invention. Referring to Fig. 3, I have shown the various drums as being mounted upon a suitable base 26 which also supports a boiler 65 27, for providing steam to an engine whose piston rod is shown at 28. It will be understood that any other motive power such as an electric motor may be employed if found desirable. The engine is connected to a shaft 70 29 which through suitable gearing operates the shafts carrying the various drums.

It is common practice to provide gearing which will rotate the drums and it is also common practice to provide various clutches 75 for engaging and disengaging the drums so that they may be rotated by the gearing or may run free.

I have not deemed it necessary to show this mechanism as it is well known in the 80 art and forms no part of this invention. It is sufficient to say that the drums are provided with the usual means of operation.

In addition to the usual means of operation referred to above, the drum 11 has secured thereto a ratchet 30, cooperating with a pawl 31 pivoted upon the frame of the engine. The drum 11 is also provided with a suitable brake shown as a band 32, adapted to be operated by a foot pedal 33, the band 90 32 encircling and cooperating with a suitable portion 34 on the drum. It is also to be understood that the drum 11 may be operated in the usual manner through gearing, and may also be operated independently of 95 the other drums.

In operation, when a log 21 or the like is to be skidded towards the head mast, the carriage is run out upon the main cable by winding in the outhaul cable and permitting 100 the slack pulling cable and skidding cable to run free. When the carriage has reached a point above the log or other load 21, the operation is stopped in the usual manner and then the lifting cable is permitted to pay out, 105 thus lowering the drop section of the carriage by its own weight, into the canyon or valley. When it has been lowered to a point

which is conveniently close to the log, the slack pulling cable may be operated in the usual manner to take up the slack in the skidding cable, and then tongs 20 may be attached to the log. The lifting cable may then be wound in to lift the drop section of the carriage and raise the log to the desired height above the ground. The slack pulling cable and skidding cable are then wound in at the same time that the outhaul cable is permitted to pay out, and thus the log may be brought in to the head mast. Or if desired, the log may be dragged in along the ground without raising the drop section 15 of the carriage.

The above arrangement provides a flexible means for operating in rough country, particularly where the span of the cable is long and the depth of the valley is relatively great. Where the span between the two masts is great, trouble has been experienced in lowering the implement such as the tongs, to a place where the load is to be placed thereon. Even with the use of the slack 25 pulling cable, it has been difficult to take up the slack in the skidding cable between the head mast and the carriage. According to my invention, however, this difficulty is overcome by lowering a part of the carriage to 30 the vicinity of the load. If necessary, the drop section of the carriage may be lowered as shown in Fig. 4, to a position close to the ground, so that the skidding cable 16 will lie along the surface of the ground and thus 35 may be more easily operated by the slack pulling cable 22. If desired, the log 21 or other load may then be dragged along the surface of the ground to the desired destination, or the load may be kept clear of the 40 ground by raising the drop section of the carriage to the requisite height.

The position of the carriage and particularly of the drop section, may be accurately controlled by operation of the pawl and 45 ratchet or the brake, or by both together, as will be understood by those skilled in the art.

In Fig. 2, there is shown a modification of my invention and referring thereto, it will be seen that this figure shows the main cable 1 and the head and tail mast 2 and 3, as in Fig. 1. However, the carriage is of 50 slightly different construction, in that the trolley section 4' is provided with only one sheave 8' through which passes the lifting cable 7. The drop section 6' of the carriage is provided with two sheaves 9', through 55 which the lifting cable passes, and this lifting cable is secured to the tail mast 3 and to the drum 11, in the same manner as in Fig. 1.

Except as described above, the modification of Fig. 2 operates in a manner identical with that described in connection with the embodiment of Fig. 1. The skidding cable 16, slack pulling cable 22 and outhaul cable 65 12, are arranged in the same manner, the

skidding cable being connected to the tongs 20, whereby the log 21 may be handled in the same manner as that described above.

I claim:

1. In an overhead cableway system, a stationary main cable, a carriage running on said cable and comprising a drop section, a sheave carried by said drop section, a skidding cable running over said sheave, means for lowering said drop section in respect to the rest of the carriage, and means for operating said skidding cable. 70

2. In an overhead cableway system, a stationary main cable, a carriage running on said cable and comprising a drop section, a skidding cable carried by said drop section, means for lowering said drop section in respect to the rest of the carriage, means for operating said skidding cable, and a slack 80 pulling cable connected to said skidding 85 cable and to said drop section.

3. In an overhead cableway system, a stationary main cable, a carriage running on said cable and comprising a drop section, a sheave carried by said drop section, a skidding cable running over said sheave, means for lowering said drop section in respect to the rest of the carriage, means for operating said skidding cable, and an outhaul cable 90 connected to said drop section. 95

4. In an overhead cableway system, a stationary main cable, a carriage running on said cable and comprising a drop section, a skidding cable carried by said drop section, means for lowering said drop section in respect to the rest of the carriage, means for operating said skidding cable, a slack pulling cable connected to said skidding cable and to said drop section, and an outhaul cable also connected to said drop section. 100 105

5. In an overhead cableway system, a head mast and a tail mast, a main cable stretched between said masts, a carriage having a trolley section running on said cable and a drop section, a lifting cable secured to said tail mast and running over sheaves on said sections and on said head mast, said drop section being supported by said lifting cable, means to operate said cable to raise and lower said drop section in respect to said trolley section, a skidding cable carried by said drop section, and a slack pulling cable operatively connected to said skidding cable and to said drop section. 110 115

6. In an overhead cableway system, a head mast and a tail mast, a main cable stretched between said masts, a carriage having a trolley section running on said cable and a drop section, a lifting cable secured to said tail mast and running over sheaves on said sections and on said head mast, said drop section being supported by said lifting cable and carrying a sheave for a skidding cable, means to operate said cable to raise and lower said drop section in respect to said 120 125 130

trolley section, a skidding cable running over said sheave on said drop section, and an outhaul cable also secured to said drop section.

- 5 7. In an overhead cable way system, a head mast and a tail mast, a main cable stretched between said masts, a carriage having a trolley section running on said cable and a drop section, a lifting cable secured to said
- 10 tail mast and running over sheaves on said

sections and on said head mast, said drop section being supported by said lifting cable, means to operate said cable to raise and lower said drop section in respect to said trolley section, a skidding cable carried by 15 said drop section, a slack pulling cable operatively connected to said skidding cable and to said drop section, and an outhaul cable also secured to said drop section.

JOSEPH H. DICKINSON.
